DRAFTING INSTRUMENT

Raymond I. Martin, Dayton, Ohio

Application October 19, 1934, Serial No. 749,084

11 Claims. (Cl. 33—104)

This invention relates to drafting instruments and, in particular, to such instruments employed in tracing the outlines of various objects from standard templates.

5 One object of my invention is to provide a drafting instrument having a plurality of apertures arranged in a series, these apertures having such outlines as to enable the tracing and reproduction of the outline of standard bolts, nuts and screws 10 of a given size.

Another object of my invention is to provide a drafting instrument having a plurality of series of apertures, each series having outlines of such 15 natures as to enable the tracing of the exact sizes of the heads, shafts and nuts of various standard bolts and screws.

Another object is to provide a drafting instrument with a plurality of sets of standard curves, each set of curves containing individual templates adapted to reproduce some portion of 20 the outline of a standard bolt, nut or screw of a given size, there being a set of such curves for each such standard size in the sizes ordinarily used, so that the necessity for the use of 25 the compass and scale or any other triangle, as well as reference to charts for sizes in the laying out of standard bolts, nuts or screws is entirely eliminated and such work correspondingly facilitated.

30 Another object is to provide such a combination of sets of bolt, nut and screw templates in connection with a draftsman's triangle, whereby these various elements may be exactly aligned relative to the T-square and drawing board.

35 Another object is to provide a drafting instrument consisting of a thin flat piece of material having sets of apertures adapted to reproduce the contours of standard nuts, bolts and screws and also the radii of various circles and arcs in common sizes.

40 Another object is to provide such sets of template curves for the contours of bolts, nuts and screws so aligned within a draftsman's triangle or other body having a right angle that all screw, 45 bolt and nut templates may be aligned in the two horizontal positions, the two vertical positions, and two 45-degree angular positions without necessitating turning the triangle over in order to alter the positions thereof.

50 Another object is to provide such a plurality of sets of nut, screw or bolt templates wherein each set is provided with a plurality of small holes or index points by the aid of which the templates may be located in their proper positions and 55 the center lines, thicknesses and widths of these

machine elements accurately laid out. By certain of these holes the body diameter is also accurately indicated.

In the drawings:

Figure 1 is a plan view of the drafting instrument of my invention, with the various apertures made three-fourths of their normal sizes in order to facilitate illustration;

Figure 2 is a side elevation thereof;

Figure 3 is a fragmentary plan view of a single 10 series of apertures or templates adapted to reproduce the contours of the nuts, bolts or screws of a given size;

Figure 4 is a plan view of a cap screw, as laid out with the instrument of my invention;

Figure 5 is a side elevation of the cap screw layout shown in Figure 4;

Figure 6 is a plan view of a bolt having the same size of shaft or shank as the cap screw of Figures 4 and 5, but with the usually larger head 20 called for by standard specifications;

Figure 7 is a side elevation of the bolt layout shown in Figure 6;

Figure 8 is a plan view similar to Figures 4 and 6, but showing the layout for a socket fillister head 25 screw;

Figure 9 is a side elevation of the layout shown in Figure 8;

Figure 10 is a plan view similar to Figures 4, 6 and 8, but showing the layout of a fillister 30 head screw;

Figure 11 is a side elevation of the layout shown in Figure 10;

Figure 12 is a plan view of the layout of an oval-headed or countersunk screw;

Figure 13 is a side elevation of the layout shown in Figure 12;

Figure 14 is a plan view of the layout of a flat-headed or countersunk screw;

Figure 15 is a side elevation of the layout shown 40 in Figure 14;

Figure 16 is a plan view of the layout of a hexagonal check or jam nut, and also of a standard nut;

Figure 17 is side elevation of the layout shown 45 in Figure 16, for a check or jam nut;

Figure 18 is a side elevation of the layout of a standard hexagonal nut.

Referring to the drawings in detail, Figure 1 shows the drafting instrument of my invention as 50 consisting of a body 1, preferably of thin material, and provided with edges 2 and 3 at right angles to one another. The remaining edges may be of any suitable character, large and small angular edges 4, 5, 6 and 7 being shown for purposes of 55

illustration. These edges 2 to 7 inclusive are so arranged that the draftsman can draw lines of fifteen degrees, thirty degrees, forty-five degrees, sixty degrees, seventy-five degrees and ninety degrees from a horizontal line drawn by means of the T-square or straight edge. The drafting instrument may be provided with a knob or handle 8 by which it is conveniently located and manipulated.

10 The body 1 is provided with a plurality of sets of apertures, each set being adapted to reproduce the outline or contour of a standard hexagonal head bolt, standard hexagon head cap screw, standard hexagonal nut, standard hexagon check or jam nut, standard fillister head screw and socket fillister head screw, and flat-headed screw.

15 Index points consisting of accurately located small holes are also provided to show the various thicknesses and positions of the curves, and used by inserting a pencil.

20 The sets of contours and templates are arranged in such a manner as to indicate the characteristics of the previously mentioned nuts, bolts 25 and screws for the standard sizes of shank of $\frac{1}{4}$ ", $\frac{5}{16}$ ", $\frac{3}{8}$ ", $\frac{7}{16}$ ", $\frac{1}{2}$ ", $\frac{5}{8}$ " and $\frac{3}{4}$ ". The same sets include the circles or arcs thereof having diameters from $\frac{1}{8}$ " to $\frac{3}{4}$ " by sixteenths, $\frac{1}{8}$ " to 1" by 30 eighths, and $\frac{1}{4}$ " to 2" by quarters.

25 Taking the $\frac{1}{2}$ " size as a convenient example (Figures 1 and 3), it will be noticed that the body 1 is provided with a circular hole 10, having a $\frac{1}{2}$ " diameter. The aperture 10 is used for drawing the outline of the shank or body of a $\frac{1}{2}$ " standard bolt or screw, and is provided with the index mark 11, pointing toward the center thereof. Immediately above this is a template 12 having the curved edges 16, 17 and 18 and used in conjunction with the index holes 13, 14 and 15 to produce the side elevation (Figure 5) of a standard $\frac{1}{2}$ " cap screw. The curved edge 19 and the side portions 20 of the template 12 are employed in conjunction with the index holes 13, 14 and 15 to produce the side elevation of the socket fillister head screw shown in Figure 9. The index point 15 is used in cooperation with the arcs 16, 17 and 18 to produce a side elevation of a standard $\frac{1}{16}$ " check or jam nut. The widths and thicknesses of the nuts and the widths 35 of the bolt heads are a full size larger than the widths for the cap screws. The thickness of the bolt head, however, is that of its normal size. Thus for the $\frac{1}{2}$ " bolt 21 shown in Figure 7, its nut 22 shown in Figure 18, and its check nut 23 shown in Figure 17, the template 24 of the $\frac{5}{8}$ " set is used for the side elevation, together with the index points 25, 26 and 27 for the nut, and 13, 14 and 15 for the bolt head. The plan view of the $\frac{1}{2}$ " bolt head is drawn by using the templates 47 and 48. (It will be recalled that Figure 1 is drawn to a three-quarter scale, hence the template sizes shown are not the exact sizes of the objects to be drawn by the instrument itself.) Thus the head of the bolt 21, as well as its regular nut 22 and its check nut 23 have the upper curved outlines drawn with the curved edges 28, 29 and 30 of the $\frac{5}{8}$ " template 24. The body of the $\frac{1}{2}$ " bolt, however, obviously has the same diameter as the body of $\frac{1}{2}$ " screws, even though the head sizes are larger.

30 The sides 20 of the upper portion of the template 12 are used in conjunction with the index hole 15 to produce the side elevation of the standard fillister head screw shown in Figure 11. The

top thereof is drawn as the chord of the arc 19, and the body by points 13 and 14.

35 Immediately above the template 12 is a circular template 35 having the index marks 36 and 37 by which its center may be found and aligned. The template 35 is of the correct diameter for producing the plan views of the heads of the various screws shown in Figures 8, 10, 12 and 14. The screw head in Figure 8 is that of a standard $\frac{1}{2}$ " socket fillister head screw; that of Figure 10 is for a standard fillister head screw without the socket; that of Figure 12 is for an oval head screw, and that of Figure 14 is for a flat head or countersunk screw. It will be observed that, where possible, all of the templates in each set are aligned upon the same center line, as shown in Figure 3, so that the various individual templates may be quickly aligned by its guidance.

40 The fourth template in the set (Figure 3) is the hexagonal template 38 which is of the exact size necessary for drawing the plan view of the standard $\frac{1}{2}$ " cap screw shown in Figure 4. The diameter of this template 38 between its parallel sides is the same as that of the screw heads shown in Figures 8 to 15 inclusive. The template 38 is provided with the guide mark 39 used in aligning its center. From the foregoing remarks, it will be recalled that the template 38 is also used to outline the heads of the bolt, nut and check nut 45 of a standard $\frac{1}{16}$ " size.

45 The fifth template in each set (Figure 3) is the small hexagonal template 40 having the guide marks 41 and 42 for aligning its center. The hexagonal template 40 is employed to produce the hexagonal countersunk portion of the socket fillister head screw shown in Figures 8 and 9.

50 The sixth template in each set (Figure 3) consists of an aperture 43 having an arcuate top 44, flaring sides 45 and a horizontal bottom 46. This template is used to draw the outline, in side elevation, of the standard oval head screw shown in Figures 12 and 13; also Figure 15.

55 It will be understood that the six members of each set of templates are not always in the same relative locations nor in the same order. Their locations are so placed that the maximum number of templates can be distributed over the size of body 1 which is employed.

In addition to the six individual templates 10, 12, 35, 38, 40 and 43 of each set, certain other 50 templates are added in order to increase the range and efficiency of the device. For example, the arcuate slot 50 possesses the arcuate edge 51 which may be used with the index hole 52 to produce an arc of $\frac{5}{8}$ " radius. The opposite edge 53 thereof may be used with the same index hole 52 to produce an arc of $\frac{3}{4}$ " radius. The arcuate slot 54 has an arcuate edge 55 which may be used in connection with the index hole 56 to produce a circle of $\frac{5}{8}$ " radius, whereas 60 the opposite edge 57 when used with the same index hole will produce an arc of 1" radius. Additional circles are provided so as to give a range of diameters covering the ordinary size likely to be encountered by the draftsman. It is obviously unnecessary to designate all of the individual templates in the various sets, as it will be seen from Figure 1 that each set is substantially a duplicate of the others except in size.

65 The use of the drafting instrument of my invention is sufficiently described under the disclosure of the individual templates. It will be recalled that the bolt, nut and check nut sizes are obtained from the set next larger than that of the body or shank being used; and it also 70 75

is necessary to use the outer index points 25 and 26 to determine the thickness of the regular nut, and the central index point 27 to determine the thickness of the check nut in each case.

5 It will be understood that I may employ a greater or lesser number of sets of these templates, or may omit certain individual templates, without departing from the scope of the invention. It will also be understood that I may employ any convenient shape for the body 1 as may be suitable for the conditions under which the instrument is to be used. I also do not limit myself to the particular arrangement of the individual templates shown, as these may be altered to enable the best distribution of the plates within a given shape of body 1.

The various outlines which may be drawn by the use of my drafting instrument enable the draftsman to dispense entirely with his compasses, drafting scales, dividers, triangles and data books for standard bolts, screws and nuts. When such a machine element is to be drawn, the draftsman merely observes the size thereof and selects the corresponding size from the sets of templates in the manner already described, always observing the caution of selecting the next larger size for bolt heads, nuts and check nuts.

The various articles and sizes which may be produced with the aid of the preferred form of drafting instrument shown in Figure 1 include the hexagon head, cap screw, bolt, nut and check nut; and the socket fillister head, standard fillister head, oval head and flat head screws. These may be drawn in all sizes, together with their body diameters and center lines, for $\frac{1}{4}$ ", $\frac{5}{16}$ ", $\frac{3}{8}$ ", $\frac{7}{16}$ ", $\frac{1}{2}$ ", $\frac{5}{8}$ " and $\frac{3}{4}$ " sizes. In addition to these, all circles may be drawn from $\frac{1}{8}$ " to $\frac{3}{4}$ " diameters by sixteenths, from $\frac{1}{8}$ " to 1" diameters by eighths and from $\frac{1}{4}$ " to 2" diameters by quarters. The plans and side elevations of the flat head and oval head screws of the $\frac{1}{8}$ ", $\frac{1}{4}$ ", $\frac{5}{16}$ " and $\frac{3}{8}$ " sizes may also be drawn. The $\frac{1}{2}$ " screw has been shown in Figures 3 and 8 to 11 inclusive and also 16, 17 and 18, and $\frac{3}{8}$ " screw in Figures 12 to 15 inclusive, because of the convenience of describing a large size on the drawings. As used for the $\frac{7}{8}$ " cap screw and $\frac{3}{4}$ " nut, the template 60 consists of the separated portions 61, 62 and 63 (Figure 1), these being thus divided up in order not to weaken the instrument by cutting large elongated apertures therein. In this size, the edge of the triangle or body 1 is used in connection with the curves 61, 62 and 63. In addition to the various sizes 61, 62 and 63. In addition to the various sizes 55 of machine elements listed, the draftsman may draw angles of fifteen degrees, thirty degrees, forty-five degrees, sixty degrees, seventy-five degrees and ninety degrees, as previously stated.

In a few instances, the use of the cap screw template for the next size smaller nut produces a slight variation from the standard size. In these few instances, however, the templates are made to a means size so that only a very slight variation from standard occurs. These slight variations, however, do not detract from accuracy of use of the drawings produced by their aid.

Thus it will be seen that the placing of the template apertures in the body and spaced apart from the edges thereof enables the edges to be made smooth and continuous for drawing other lines or angles, as well as protecting the templates from dents or nicks.

It will be understood that I desire to comprehend within my invention such modifications as

may be necessary to adapt it to varying conditions and uses.

Having thus fully described my invention, what I claim as new and desire to secure by Letters Patent is:

1. A drafting instrument comprising a body, and a set of apertures in said body, said set comprising individual template apertures having the partial outlines of the heads of standard sized bolts, said apertures having scalloped portions 10 for the side-elevational head outlines, each scalloped portion having three index apertures in spaced relationship therewith, one pair of said index apertures being adapted to indicate the shank diameter of said bolt, the third index aperture being spaced apart from said scalloped portion by the distance equivalent to the thickness of the standard hexagonal head the partial outline of which is represented by said scalloped portion. 20

2. A drafting instrument comprising a body, and a set of apertures in said body, said set comprising individual template apertures having the partial outlines of the heads of the bolts in a given standard size thereof, said outlines comprising a circular aperture for the body portion, hexagonal apertures for the hexagonal portions, a scalloped portion for the side elevation views of the hexagonal portions, and a pair of index apertures in spaced relationship with said scalloped portion and adapted to indicate the shank diameter of said bolts. 25

3. A drafting instrument comprising a body, and a set of apertures in said body, said set comprising individual template apertures having the partial outlines of the heads of the bolts in a given standard size thereof, said outlines comprising a circular aperture for the body portion, hexagonal apertures for the hexagonal portions, a scalloped portion for the side elevation views 40 of the hexagonal portions, and three index apertures in spaced relationship with said scalloped portion, one pair of said index apertures being adapted to indicate the shank diameter of said bolts, and the third of said index apertures being spaced apart from said scalloped portion by the distance equivalent to the thickness of the standard hexagonal head the partial outline of which is represented by said scalloped portion. 45

4. A drafting instrument comprising a body, 50 and a set of apertures in said body, said set comprising individual template apertures having the partial outlines of the heads of the bolts in a given standard size thereof, said outlines comprising a circular aperture for the body portion, hexagonal apertures for the hexagonal portions, a scalloped portion for the side elevation views 55 of the hexagonal portions, and a pair of index apertures in spaced relationship with said scalloped portion and adapted to assist in the positioning thereof, one of said index apertures being spaced apart from said scalloped portion by the distance equivalent to the thickness of the standard bolt or another head corresponding thereto, the other index aperture having a spacing equivalent to the thickness of the standard check nut head the partial outline of which is represented by said scalloped portion. 60

5. A drafting instrument comprising a body, and a plurality of sets of template apertures arranged in said body, each set comprising a series of apertures having the outline sizes corresponding to the outline dimensions of standard bolts for a given standard size of shank, the outline dimensions of the template aperture for the hex- 75

- agonal bolt and nut head for a given size of shank being of substantially the same size as the outlines of the cap screw head used with the next larger standard size of shank.
- 5 6. A drafting instrument comprising a body and a plurality of apertures in said body spaced apart from the edges thereof, the opposite portions of said apertures having the outline characteristics in side elevation of different sizes of standard sized bolt heads and screw heads, respectively, whereby the different edge portions of said apertures cooperate successively to reproduce the outline appearance of said standard bolts or screws.
- 15 7. A drafting instrument comprising a body and a set of apertures in said body spaced apart from the edges thereof, said set comprising a plurality of individual template apertures, the opposite portions of said apertures having the outline characteristics in side elevation of different sizes of bolt heads and screw heads, respectively, in standard sizes thereof, the opposite sides of said apertures being spaced apart from each other by a distance which is a substantial proportion of the width of said apertures, whereby the different edge portions of said apertures cooperate successively to reproduce the outline appearance of said standard bolts or screws.
- 20 8. A drafting instrument comprising a body and a set of apertures in said body, said set comprising individual template apertures having the partial outlines of the heads of standard sized bolts, one portion of each aperture having the outline characteristics of one size of bolt and another portion of the same aperture having the outline characteristics of another size of bolt, said apertures having scalloped portions for the side-elevational head outlines, whereby the different edge portions of said apertures cooperate successively to reproduce the outline appearance of said standard bolts.
9. A drafting instrument comprising a body and a plurality of sets of template apertures arranged in said body and spaced apart from the edges thereof, each set comprising a series of apertures having the outline characteristics of standard bolts or screws in side-elevational silhouette, opposite portions of said apertures having different outline characteristics, whereby the different edge portions of said apertures cooperate successively to reproduce the outline appearance of said standard bolts or screws. 5
10. A drafting instrument comprising a body and a plurality of sets of template apertures arranged in said body and spaced apart from the edges thereof, each set comprising a series of apertures having the outline characteristics of standard bolts or screws in side-elevational silhouette, opposite portions of said apertures having different outline characteristics, said sets having the individual templates of each set arranged in proximity to one another whereby to facilitate the instant selection of the proper template for the particular size required and eliminate the danger of selecting the wrong size of template, whereby the different edge portions 20 of said apertures cooperate successively to reproduce the outline appearance of said standard bolts or screws. 25
11. A drafting instrument comprising a body and a plurality of sets of template apertures arranged in said body and spaced apart from the edges thereof, each set comprising a series of apertures having the outline characteristics of standard bolts or screws in side-elevational silhouette, opposite portions of said apertures having different outline characteristics, said body having angularly disposed sides, whereby the different edge portions of said apertures cooperate successively to reproduce the outline appearance of said standard bolts or screws. 30 35 40

RAYMOND I. MARTIN.
